COIL UNIT

Erwin E. Franz, Cranford, N. J., assignor to
 Western Electric Company, Incorporated, New
 York, N. Y., a corporation of New York

Application April 5, 1941, Serial No. 387,017

6 Claims. (Cl. 175—356)

This invention relates to coil units, and more particularly to electrical coil units used in the communications arts.

An object of the invention is to provide a simple, efficient and highly practical electrical coil unit.

With this and other objects in view, one embodiment of the invention comprises an electrical coil unit having companion head members formed for the winding of a coil thereon and with grooves in one of the members for the securing of a selected number of like terminals in place, the terminals having shoulders over which leads from the coil may extend and adjacent diagonally extending portions about which the leads may be wound.

Another embodiment of the invention comprises U-shaped heads similar in structure to the ends of one of the heads of the other embodiment and formed also to receive a selected number of terminals, reversible elements being illustrated in this embodiment with oppositely disposed serrations for use in removing either separate leads from the coil or leads in the form of loops and maintaining the course of winding of the coil.

Other objects and advantages will be apparent from the following detailed description when considered in view of the accompanying drawings, wherein

Fig. 1 is an end elevational view of an electrical coil unit, portions thereof being broken away to illustrate one embodiment of the invention;

Fig. 2 is a side elevational view of the unit shown in Fig. 1, portions thereof being broken away;

Fig. 3 is a top plan view of the structure shown in Fig. 2, portions thereof being broken away;

Fig. 4 is an end elevational view of another embodiment of the invention, portions thereof being broken away;

Fig. 5 is a fragmentary side elevational view of the structure shown in Fig. 4;

Fig. 6 is an enlarged fragmentary detailed view taken substantially along the line 6—6 of Fig. 5;

Fig. 7 is a fragmentary detailed view similar to the showing in Fig. 4, illustrating one of the lead guiding elements;

Fig. 8 is a perspective view of the head members, of the first embodiment, spaced from each other to illustrate the structure thereof, and

Fig. 9 is a perspective view of one of the heads of the other embodiment.

Referring now to the drawings, attention is first directed to Figs. 1 to 3 inclusive and Fig. 8, which illustrate companion heads 10 and 11 which are substantially U-shaped in general contour as well as in cross section and formed, at their inner portions, to completely surround a central core member 12.

The adjacent ends of the heads 10 and 11 are spaced from each other, as at 13, excepting where the portions 14 of the heads 11 adjacent the core project upwardly to close the spaces. These spaces 13 at each side of the heads and at each end thereof make possible the projection of leads, hereinafter described, therethrough. The heads 10 and 11 have flange or wall portions 16 and 17, respectively, joining in completing the U-shaped cross sectional contour of the heads and forming aligned compartments in which coils 18 and 19 may be wound. In the present embodiment the central flanges or walls are illustrated dividing the heads into separate compartments for the different coils 18 and 19, but if desired the central wall may be eliminated if but a single coil is desired to be wound on the heads. One important feature is pointed out at this point, this being the fact that the winding of the coil or coils upon the heads serves as a means to secure the heads together and upon the central core member 12, eliminating the necessity of other securing means to accomplish this purpose.

The head 10 has U-shaped portions 20 integral with the outer walls 16 thereof and projecting outwardly as illustrated in Fig. 1. A series of vertical slots 21 is formed at spaced positions in the portions 20, these slots having cooperating recesses 22 and 23 communicating therewith at their upper and lower extremities and extending at right angles with respect thereto, as shown in Fig. 2. The lower surfaces of the portions 20 adjacent the openings 13 are serrated, as at 25, forming a multiplicity of retaining grooves for leads 26 of the coils 18 and/or 19.

Like terminals 28 of the strip type illustrated taken from a supply are receivable in selected slots 21 and have integral lugs 30 receivable in the recesses 22 adjacent the selected slots, while the lower ends of the terminals have integral tabs 31 which may be bent laterally into the adjacent recesses 23 to thus secure the terminals in the slots. The portions of the terminals disposed in the slots 21 have diagonally extending notches 33 extending partially into the slots 21 and forming portions 34 with diagonal surfaces

35 about which the leads 26 may be wound. Integral with the portions 34 and at the lower extremities thereof, outwardly projecting portions 36 form shoulders 37 upon which the leads may rest when wound about the portions 34. The structure thus formed may be positioned to submerge the portions 34 and 36 of the terminals in a molten solder bath to solder the leads to the terminals, this requiring, of course, separate soldering steps for the terminals upon each side of the structure.

The core structure may then be completed by securing, in any desired manner such as by the aid of non-magnetic channel members 38 and rivets 39, outer core members 40 to the central core member 12. In completing the core structure mounting studs 41 may be included for use in subsequently mounting the coil unit to a suitable support such as a frame (not shown). The assembly may now be lowered into a contained 42 and an insulating covering 43 positioned to close the open end of the container 42, the covering being held in place by integral tabs 44 of the covering bent inwardly as illustrated in Figs. 1 to 3 inclusive.

With this embodiment of the invention a desired number of terminals, depending upon the number of leads to be taken from the coils 18, 19, are mounted in selected slots 21 in the head 10. The leads 26, some of which may be taken near the beginning of the winding of the coils and others at the ends of the coils while still others may be taken intermediate the ends and the beginning of the coils, are projected outwardly upon either side of the heads or at either end thereof through the openings 13, where they are freed of their insulation. When this has been accomplished each lead is passed through a notch, in the adjacent serrated surface 25, which is in alignment with the point where the lead leaves the coil, after which the lead may be extended outwardly and upwardly toward its terminal. The notch or serrated portion in the serrated surface serves to hold the lead in a definite position with respect to the point where it leaves its coil, to eliminate possible disturbance in the winding of the coil. The lead is then drawn over the shoulder 37 of its terminal and wrapped about the portion 34. In the wrapping of the lead about the portion 34, the lead enters a substantially V-shaped groove formed by the surface 35 of the terminal and the adjacent wall of the head, the vertex of which is smaller than the diameter of the lead, making it possible for the lead to be wedged therein. In reality, the wedging effect is enhanced by four edges, two edges of the surface 35 and the edges of the adjacent slot 21. As soon as the lead is wrapped about the portion 34 and wedged in place, a continued pull on the free end of the lead will cause breakage thereof adjacent the last edge of the surface 35, this edge serving to shear the free end of the lead from that wound about the portion 34 of the terminal.

The embodiment illustrated in Figs. 4 to 7 inclusive and Fig. 9 has features in common to those shown in Figs. 1 to 3 inclusive, in that the terminals are identical in structure, the heads differing only in the fact that they do not surround a central core member. For example, the heads 50 are U-shaped in general contour and identical to the U-shaped portions 20 of the head 10. Therefore, should the central and outer walls 16, which are disposed between the portions 20, be removed, the remaining structure, that is, the

portions 20 would be identical to the heads 50. The heads 50, only one of which is shown, are disposed at opposite sides of a central core member 51 about which a coil 53 is wound, the coil serving the same function as the coils 18 and 19 in the first embodiment, of securing the heads 50 in place, eliminating the need of additional securing means to mount the heads on the central core member. In this embodiment terminals 54, identical in structure to the terminals 28, and having projecting lugs 55, are selectively disposed in a plurality of slots 56 in the side walls of the heads 50, so that the lugs 55 will rest in lateral recesses 57 while integral tabs 58 of the terminals 54 at the lower ends thereof may be bent laterally into recesses 59. The lower portions of the terminals 54 have notches 60 extending diagonally into the slots 56, forming surfaces 61 on portions 62 which cooperate with the adjacent walls of the heads in forming recesses to wedgily receive leads 63 of the coil. The terminals also have portions 64 adjacent their lower ends, forming shoulders 65 upon which portions of the leads may rest in being wound upon the portions 62 of the terminals. Attention is also directed to the serrated under surfaces 66 of the heads, forming notches for receiving the leads 63.

An additional feature is added to this embodiment which may also be employed with the embodiment illustrated in Figs. 1 to 3 inclusive should it be desirable to eliminate the central wall 16 of the head 10. This feature includes elements 67 of the contour illustrated in Fig. 7. These elements are formed of suitable material, for example, from cellulose acetate sheets, and are notched at their ends, as at 68, to interengage the inner portions of the side walls of the heads 50. The other edges of the elements are serrated, as at 69, providing series of notches to receive leads in forming taps from the coil. The functions of the elements 67 are to hold the convolutions of the coil against disturbance or displacement, particularly at the leads, and to insulate the leads from each other and from the convolutions of the coil. The use of these elements is of utmost importance in the removal of leads intermediate the ends of the coil to maintain the winding course of the coil.

In viewing Fig. 7, let it be assumed that the coil 53 is only partially wound and that it is desirable to remove a double lead in the form of a loop therefrom. At this point one of the elements 67 may be disposed in place over the convolutions of the coil thus formed including the last convolution from which a lead 70 will extend. The wire of this last convolution which passes beneath the element 67, as illustrated at 71, may be bent into the adjacent notch of the adjacent serrated edge 69 to hold the convolutions, particularly the last one, in place while drawing the lead, outwardly, through an aligned notch in the serrated surface 66 and upwardly to its respective terminal. In passing upwardly, the wire is extended over the shoulder 65 and around the portion 62. In passing or wrapping the lead wire around the portion 62, the lead may be drawn downwardly into the V-shaped recess, where it will be wedged in place. Following this step, the lead wire is then passed downwardly beneath the adjacent wall of the head through another, but adjacent, notch in the serrated surface 66 and upwardly to a position above the upper edge of the first element 67. Another element 67 may then be disposed over the first element and in a like manner held in place

through its inner connection with the side walls of the head, positioning the last mentioned portion of the lead wire between the two elements. At this time the lead wire may be disposed in a desired notch of the upper surface of the last mentioned element, so that it may be adjacent the last convolution of the coil and in order that the winding of the coil may be continued with the convolutions lying in parallel adjacent positions.

If desired, two separate leads may be formed by the aid of the elements 67 instead of a single loop, the separate leads being directed to separate terminals and secured thereto in the manner previously described and illustrated in Fig. 6.

When the coil has been completed and the desired leads secured to their respective terminals, the structure thus far completed may be disposed relative to a solder bath to submerge the portions 62 and 64 of the terminals, with the leads secured thereto, in the bath to solder the leads to the terminals. The coil structure may then be completed by securing outer core members 73 to the central core member 51 by any suitable means such as angle members 14, formed of suitable non-magnetic material, and rivets 75. The upper rivet 75 may also secure mounting studs 76 in place for the mounting of the coil unit shown in this embodiment to a suitable support such as a frame. The coil unit thus far completed may be disposed in a casing 77, the open end of which may be closed by a plate 78, formed of suitable insulating material and having apertures through which the terminals 54 and the studs 76 project, secured in place through the aid of tabs 79 integral with the casing and bent inwardly as in Fig. 3.

The embodiments of the invention herein disclosed are merely illustrative and may be modified and departed from in many ways without departing from the spirit and scope of the invention as pointed out in and limited solely by the appended claims.

What is claimed is:

1. An electrical coil unit comprising a hollow head, a coil having a lead and wound with convolutions thereof disposed in the head, a terminal carried by the head and formed for the securing of the lead thereto, and an element formed for interengagement with the head and having recesses disposed adjacent the convolutions and employed to selectively receive the lead at its juncture with any desired one of the adjacent convolutions to hold the convolutions against displacement during the securing of the lead to the terminal.

2. An electrical coil unit comprising a hollow

head including side members, a coil having leads and wound about the head, between the side members thereof, and about a core to secure the head in place about the core, terminals carried by the side members, and a reversible element interengageable with the head between the side members thereof and having recesses disposed adjacent the convolutions and adapted to selectively receive the lead at its juncture with any desired one of the adjacent convolutions to guide the leads to their respective terminals on either member and hold the convolutions against displacement.

3. In an electrical unit having a coil with leads and wound on a core, a head having a portion interposed between the coil and the core and a side member, having a slot therein, disposed free of the coil and core, and a terminal rigidly mounted in the said slot and having a notch therein extending into the slot to receive a lead from the coil, a surface of the terminal at the notch and the adjacent edges of the slot cooperating to wedgely hold the lead against displacement.

4. In an electrical unit having a coil with leads and wound on a core, a head having a portion interposed between the coil and the core and a side member, having a slot therein, disposed free of the coil and core, and a terminal disposed in the said slot and having a notch therein extending diagonally into the slot to receive a lead of the coil and provide a surface cooperating with adjacent edges of the slot to wedgely hold the lead against displacement.

5. In an electrical unit having a coil with leads and wound on a core, a head having a portion interposed between the coil and the core and a side member, having a slot therein, disposed free of the coil and core, a terminal disposed in the said slot and having a notch therein extending diagonally into the slot to receive a lead of the coil and provide a surface cooperating with adjacent edges of the slot to wedgely hold the lead against displacement, and means to rigidly mount the terminal in the slot.

6. In an electrical unit having a coil with leads and wound on a core, a head having companion portions surrounding the core, formed for the winding of the coil thereon and having a side member on one of the portions with a slot therein, and a terminal disposed in the said slot and having a notch therein extending diagonally into the slot to receive a lead of the coil and provide a surface cooperating with adjacent edges of the slot to wedgely hold the lead against displacement.

ERWIN E. FRANZ.
